UNITED STATES PATENT OFFICE.

ISAAC WAGEMAKER, OF GRAND RAPIDS, MICHIGAN.

FILING APPLIANCE.

Application filed January 17, 1921. Serial No. 437,715.

To all whom it may concern:

Be it known that I, ISAAC WAGEMAKER, a citizen of the United States of America, residing at Grand Rapids, in the county of Kent and State of Michigan, have invented 5 certain new and useful Improvements in Filing Appliances; and I do hereby declare the following to be a full, clear, and exact description of the invention, such as will 10 enable others skilled in the art to which it appertains to make and use the same.

This invention relates to filing appliances. It is common, particularly in desks, to use 15 various filing trays in the drawers thereof, resting the trays on the bottom of the drawer and between the sides thereof, in which trays filing cards are positioned vertically, the cards carrying information filed for reference. The many different sizes of 20 filing cards used necessitates different sizes and depths of trays and when the same are placed in a desk drawer it is apparent that the same present a very uneven appearance 25 at their upper sides and that in many cases it is hard to gain proper access to the different cards in the trays especially when a tray carrying cards of relatively short height is placed alongside of a tray having 30 cards therein of greater height or between two trays carrying cards of greater height.

With my invention it is contemplated that the card holding trays shall be so constructed that the upper edges thereof, when placed in a drawer or like receptacle shall 35 be all in the same horizontal plane, substantially, the upper edges of all of the cards in the different trays being in a common plane and all cards being as free of access and examination as is possible, the ease of 40 access and examination of the smaller cards being the same as that of the larger cards. It is a primary object and purpose of the invention to make a construction accomplishing these ends. A further object of 45 the invention is to accomplish these desired ends in a very simple manner and by a construction requiring little in the way of manufacturing expense, so little in fact as to be almost negligible. Various other ob- 50 jects and purposes than those stated will appear as understanding of the invention is had from the following description, taken in connection with the accompanying drawing, in which,

Fig. 1 is a perspective view of a drawer

equipped with the filing trays of my invention all at their upper edges lying in the same horizontal plane.

Fig. 2 is a longitudinal section taken vertically and transversely of the trays in the drawer, the trays being located across the drawer, and

Fig. 3 is a perspective view of one of the trays, showing the construction thereof.

Like reference characters refer to like 65 parts in the different figures of the drawing.

As shown, the drawer is of well known and common construction, having parallel sides 1, front 2 and back 3. The trays designed to be placed in the drawer across the same have parallel sides 4, and ends 5. The trays are of different depths and those trays having less depth than the depth of the drawer into which they are to be placed 70 are equipped at each end with foot members 6 which extend from the trays in the same planes as the ends 5 of the trays and are secured permanently to and project downward from said ends. Any suitable 75 means of permanently connecting said members 6 may be used, use being made of triangular shaped corner blocks 7 in those trays of shallower depth which necessitate longer members 6.

With trays constructed as described, when the same are placed in the drawer, the lower ends of the foot members 6 rest on the bottom 8 of the drawer, the bottoms 9 of the different trays being spaced greater 80 or less distances above the bottom of the drawer. The members 6 for the different trays are of different length, dependent 85 upon the differences in depths of the trays as compared with the depth of the drawer 90 into which the same are to be placed, the design being that the upper edges of all 95 of the trays shall be substantially in the same horizontal plane. The trays, of course, may be equipped with the usual fol- 100 lower blocks and like filing construction, not shown in the drawing, as the same is no part of the present invention.

With this construction, the trays, irrespective of depth, are located in the drawer, 105 or other similar holding receptacle so as to present the filing cards therein all substantially on a level at their upper edges. This presents the cards in the best possible way for ready access and examination, and at 110

the same time the drawer with the trays therein is much more slightly in appearance than it is with different heights of trays placed on the bottom of the drawer without the elevating foot members for the trays. The invention, while simple as to construction, is very practical and is a valuable advance in the art of filing. It is to be understood that the invention is not limited in use to desk drawers but has many other places of use. The appended claims define the invention, and I consider myself entitled to such modifications in construction as come within the scope of said claims.

15 I claim:

1. In combination with a receptacle having a bottom and sides, of a plurality of separate trays of different depths located side by side in the receptacle, and means connected with the trays for positioning them in the receptacle with their upper edges in substantially the same plane, substantially as described.

2. In combination with a receptacle having a bottom and sides of a plurality of trays located in the receptacle, said trays having different depths and with bottoms located at different distances below the upper edges of the trays, of means connected to the under sides of the trays and resting on the bottom of the receptacle for locating

the trays with their upper edges all substantially in the same horizontal plane.

3. In combination with a receptacle having a bottom and sides, of a plurality of trays located side by side in the receptacle, said trays having bottoms located at different distances below the upper edges of the trays, and foot members of different heights connected to and extending downwardly from the trays and resting on the bottom of the receptacle, the depth of a tray plus the height of its foot members being substantially equal to the depth of any other tray plus the height of its foot members, whereby all of the trays have their upper edges substantially in the same horizontal plane.

4. A plurality of filing trays of different depths, each having sides, ends and a bottom, and a foot member attached at each end of each tray and projecting downwardly therefrom, the depth of a tray plus the height of its foot members being substantially equal to the depth of any other tray plus the height of its foot members, substantially as and for the purposes described.

In testimony whereof I affix my signature.

ISAAC WAGEMAKER.
